UNITED STATES PATENT OFFICE

REGINALD D. LOWE, OF ASHLAND, KENTUCKY

GENERATOR CONTROL

Application filed May 6, 1929. Serial No. 360,688.

This invention relates to a device whereby the generator of an automobile can be controlled from the dash or instrument board thereby to adapt it quickly for use during either long or short drives.

Heretofore, after a generator has been set to charge at a high rate, it has been the practice, before starting a long drive, to reset the same so as to prevent overcharging and possible injury to the battery. Unless this has been done by an expert using proper tools, a grounded circuit has frequently resulted.

It is an object of the present invention to provide simple and efficient means whereby one of the brushes can be advanced or set back readily without the use of tools and while the vehicle is in motion.

Another object is to provide a holder for the shiftable brush so insulated as to eliminate a large amount of generator trouble heretofore experienced.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

Figure 1 is an end elevation of the generator casing, a portion thereof being broken away to show the third brush and a part of its operating means.

Figure 2 is a view partly in section and partly in elevation of the generator casing and some of the parts therein.

Figure 3 is a transverse section through the third brush and its holder, said section being on the line 3-3, Figure 1.

Figure 4 is an enlarged section similar to Figure 3 but taken axially through the lugs.

Referring to the figures by characters of reference, 1 designates one end portion of the housing of generator 2, the same being provided with a removable plate 3 forming a bearing for one end of the generator shaft

4. Mounted in the housing is a ring 5 formed preferably of pressed steel to the inner and outer faces of which are secured layers 6 and 7 of fibre or other suitable insulating material.

55

Journaled in the ring 5 is one end of a shaft 8 carrying a segmental gear 9 that is located between the ring 5 and the end of housing 1. A portion of this shaft 8 extends through a notch or slot 10 in plate 3 and carries an enlargement 11 that is substantially cylindrical. The periphery of this enlargement is formed with longitudinal grooves or serrations 12 and is constantly engaged by a spring finger 13 extending from plate 3 and exerting a thrust against the enlargement 11. An operating shaft 14 is connected to shaft 8 by a universal joint 15 or any other suitable means and is adapted to extend to the dash or instrument board where it can be operated readily by the driver.

60

The ring 5 and the layers 6 and 7 of insulating material are formed with a short arcuate slot 16 concentric with the shaft 4. Slidable in this slot are studs 17 extending from one side of a slide 18. Rack teeth 19 are formed along one edge of the slide and mesh constantly with the segmental gear 9.

65

Slide 18 is located at one side of the ring 5 while at the other side of said ring is positioned a block 20 of insulating material. As shown particularly in Figure 3 this block is formed with a dove-tail 21. The block is detachably connected to slide 18 by a screw 22 that extends through the slide and through the slot 16. This screw has a shoulder 22' which binds against lock 20, the frictional contact thereagainst being such as to hold the screw normally against rotation.

70

The third brush, which has been indicated at 23, is arranged in a sleeve 24 having a dove-tail groove 25 in one wall for the reception of the dove-tail 21. The frictional engagement of the parts 21 with the walls of groove 25 will hold these parts against relative displacement under normal working conditions. A spring 26 is provided as ordinarily for holding the third brush pressed firmly against the commutator 27 of the generator.

75

80

85

90

95

100

Importance is attached to the fact that the third brush is so mounted as to be completely insulated from the supporting ring 5. This insulation is effected by the layers 6 and 7 and by the block 20 which serves to hold sleeve 24 properly spaced from the ring 5 as well as from the studs 17 carried by the slide.

By providing the resilient finger 13 and the grooved portion 11, gear 9 will be held properly in any position to which it may be rotated. Thus by turning shaft 14 and gear 9, slide 18 will be shifted either to advance or set back the third brush and correspondingly regulate the generator.

What is claimed is:

1. The combination with a generator housing, of a ring mounted therein, a shaft journaled in the ring, a slide upon one side of the ring, an insulating block at the other side of the ring and connected to the slide, a brush-carrying sleeve detachably connected to the block, and cooperating means on the shaft and slide for shifting the slide to advance or set back the brush.

2. The combination with a generator housing, of a ring mounted therein, a block of insulating material slidable relative to the ring and engaging one of the thicknesses of insulating material, a brush-carrying sleeve, a tongue and groove connection between the sleeve and block, and means for shifting the block relative to the ring to advance or set back the brush holder.

3. The combination with a generator housing, of a ring fixedly mounted therein having an arcuate slot, a slide at one side of the ring, means thereon movable within the slot for holding the slide against displacement relative to the ring, an insulating block at the other side of the ring, means extending through the slot for connecting the slide and block, a brush-holding sleeve, a separable tongue and groove connection between said sleeve and the block, an operating shaft, resilient means for retarding the rotation of the shaft, and a geared connection between the shaft and the slide.

In testimony that I claim the foregoing as my own, I have hereto affixed my signature.

REGINALD D. LOWE.
